UNITED STATES PATENT OFFICE.

SAMUEL S. HARPER, DECEASED, LATE OF NEW YORK, N. Y., BY ELEANOR L. HARPER, EXECUTRIX, OF NEW YORK, N. Y., ASSIGNEE TO AIR TURBINE COMPANY OF AMERICA, OF JERSEY CITY, NEW JERSEY, A CORPORATION OF NEW JERSEY.

WINDMILL.

1,118,343.

Specification of Letters Patent. Patented Nov. 24, 1914.

Application filed July 15, 1913. Serial No. 779,079.

To all whom it may concern:

Be it known that I, ELEANOR L. HARPER, a citizen of the United States, residing in the borough of Manhattan, city, county, and

5 State of New York, executrix of the last will and testament of SAMUEL S. HARPER, deceased, late of the borough of Manhattan, city, county, and State of New York, do hereby declare the following to be a full, 10 clear, and exact description of the invention of the said SAMUEL S. HARPER of an Improvement in Windmills, such as will enable others skilled in the art to which it pertains to make and use the same.

15 This invention relates to wind-mills of the general type disclosed in the application for patent of Samuel S. Harper, filed February 23, 1909, Serial No. 479,503. In this form of wind-mill, there is a vertical shaft 20 carrying a cage, in which is supported a plurality of vanes. Such vanes are mounted upon vertical pivots, and swing inward and outward by the pressure of the wind. A device is provided for guiding the vanes 25 and limiting their movement.

The present invention relates to improvements of this device.

The objects of the invention are to simplify the structure, reduce wear and render

30 the guiding and limiting device independent of the shaft. These and further objects will more fully appear from the following specification and accompanying drawings, considered together or separately.

35 In the drawings, Figure 1 is an elevation of a wind-mill embodying the invention. Fig. 2 is a sectional view of the same looking downward, the section being taken on the line 2-2 of Fig. 1. Fig. 3 is a plan view partly in section of a modification of the ring for determining the position and extent of the movement of the vanes; and Fig. 4 is a detail view of a further modification.

45 In all of the views, like parts are designated by the same reference characters.

Referring to Fig. 1, it will be seen that the wind-mill is supported upon a shaft 1, which is vertical. A plurality of vanes 2-2

50 are connected by pivots 3 to upper and lower rims 4, 4. These rims are connected to

and supported from the shaft 1 by means of spokes 5, 5 engaging with hubs 6, 6. This form of mill is generally shown in the co-pending application, before referred to.

55

The device for controlling the position of the vanes consists of a ring 7. This ring, as shown, surrounds the shaft 1, and is connected to and is supported by the vanes 2, 2. On the ring 7, and adjacent to each vane is 60 a supporting link 8, mounted to turn on the ring, and connected to the ring by bearings 9-9. These links are preferably connected and proportioned, as shown, so that they will produce a rigid support for the ring. 65 For the purpose of stiffening the ring and preventing it from collapsing, and at the same time to allow it to be made as light as possible, it is provided with spokes 10, 10, which preferably cross it in the manner 70 illustrated, so that a central open space is provided through which the shaft 1 passes. The ring is of such a size that it will come in contact with the pivoted edges of the vanes when the latter are swung out to the 75 maximum extent, as shown in the upper left-hand portion of Fig. 2. When the ring is in this position, the vanes shown at the lower part of the figure will swing inward to the maximum extent.

80

For the purpose of imparting tension to the spokes 10, the device shown in Figs. 1 and 2 may be used. In accordance with this embodiment of the invention, the spokes 10 are connected to annular hubs 11, 11, 85 these hubs surrounding the shaft 1. The internal opening in the hubs is sufficiently large so that their inner edges never come in contact with the shaft. The spokes 10, 10 are connected to the hubs, as shown in 90 Fig. 1, and these hubs are separated by means of stay-bolts 12, 12. Three of these bolts are shown in Fig. 2. The ends of these bolts are threaded, as shown, the threads being of opposite pitch at the two ends, and 95 the central part of the bolt is preferably squared for the application of a wrench. By rotating the bolts, the hubs are separated, and the requisite amount of tension is imparted to the spokes 10, 10.

90

95

100

Fig. 3 represents a modification in which the hubs 11, 11 are not used, the spokes ex-

tending directly from one side of the ring to the other. The ends of the spokes are shown as provided with nuts, by means of which the tension may be applied to them.

5 Fig. 4 represents still another modification, in which the spokes are arranged in the manner as shown in Fig. 3, and are provided with turn buckles, by means of which the necessary amount of tension may be imparted to them.

10 From the foregoing specification, it is apparent that by this invention there is produced a very simple and efficient device for governing the position of the vanes. The 15 vanes will incline in the direction of the wind so as to produce the most effective conversion of the wind pressure into rotating forces. At the same time, the structure is simple and does not easily get out of order, 20 and the only wear that occurs is between the outer end of the ring 7 and the pivoted edges of the vanes 2 and the connections between the links 8 and their supporting bearings.

25 While there is shown in the drawings as an embodiment of the invention illustrated, a single ring 7 secured to approximately the center of the vanes 2, it must be understood that the invention is not limited to the precise number of rings that are used, or to the 30 position thereof.

35 In accordance with the provisions of the patent statutes, I have described the principle of the invention, together with the apparatus which I now consider to represent the best embodiment thereof; but I desire to have it understood that the apparatus shown is merely illustrative and that the invention may be carried out in other ways.

Having now described the invention of 40 the said SAMUEL S. HARPER, what I claim as

new and desire to secure by Letters Patent, is:—

1. A wind mill having a plurality of vertical pivoted vanes, a cage for supporting the same and a ring connected to the vanes 45 and supported thereby, said ring, by its engagement with the vanes, limiting and determining the extent of movement of the vanes.

2. A wind mill having a vertical shaft, a 50 cage thereon, vanes pivoted upon vertical axes within the cage, a ring, connections between the ring and the vanes, these connections being the sole support for the ring, said ring, by its engagement with the vanes, limiting and determining the extent of movement of the vanes, cross members connecting the ring at opposite sides and means for imparting tension to such cross members. 55

3. A wind mill having a central supporting shaft, rims secured to the shaft and supported thereby, a plurality of vertical vanes pivoted to the rims, the pivot being adjacent to one edge of a vane, a ring surrounding the shaft, supports for the ring carried by the vanes, said ring, by its engagement with the vanes, limiting and determining the extent of movement of the vanes, spokes extending across from side to side of the ring, and leaving a central opening for the movement of the ring around the shaft, and devices for exerting stress upon the spokes. 60

65 This specification signed and witnessed this 30th day of April, 1913.

ELEANOR L. HARPER,
Executrix of the last will and testament of
Samuel S. Harper, deceased.
